SALES TICKET AND FORMS HOLDER AND
FORMS REGISTER

Joseph Zalkind, New York, N. Y.

Application June 28, 1949, Serial No. 101,886

13 Claims. (Cl. 281—44)

1

This invention relates to a holder for sales-slips or forms on which orders are written, and has as an object thereof the provision of a novel device of the character that will hold the sales-slips or order forms in a suitable compartment providing means for automatically positioning the uppermost form or forms to be written on in relation to a writing platen forming a closure for the order form holder.

A further object of the invention is to provide a holder for forms, which holder consists of a compartmentalized base member having a closure which is slideable to extend beyond an end portion of the base member to provide a hand rest so that the user of the invention may more conveniently make notations on the order form when the form to be written on is positioned on the upper surface of the closure member, which closure member acts as a writing platen.

Further and other objects of the invention may be and may become apparent to one skilled in the art from a perusal of the disclosure herein. The present showing is by way of illustration only of a preferred embodiment of the invention. It is to be understood that changes and modifications may be made in the invention without departing from the spirit thereof as defined by the subjoined claims.

Throughout the specifications and claims, the expression "order form" or "sales-slip" may be used interchangeably, and it is to be understood that either expression refers to the forms carried by the diaphragm regardless whether they are in a pad form, a collection of individual slips, manifold forms or any other material on which writing may be placed, and adaptable for use in the present invention.

In the drawings:

Fig. 1 is a perspective view showing the order form holder having its closure member extended to its operative position.

Fig. 2 is a plan view, partially broken away, showing the closure member open and in an extended position, shown in solid lines.

Fig. 3 is a sectional view taken substantially along lines 3—3 of Fig. 2, but with the closure member moved to its inoperative position which would be the case when the holder is not in use.

Fig. 4 is a side view of the holder with the closure moved to its inoperative position.

Fig. 5 is a sectional view taken substantially along lines 5—5 of Fig. 2.

Fig. 6 is an enlarged sectional partial view showing the latch means for holding the closure member in position.

2

Fig. 7 is a partial plan view of one position of the modification of the diaphragm support showing the channel member which guides one corner of the diaphragm within the base member.

Fig. 8 shows a modification of the invention embracing a sales slip holder and forms dispenser.

Fig. 9 shows the modification with the writing platen swung open to permit loading of the device, presented in a top plan view.

Fig. 10 is a sectional view taken along lines 10—10 of Fig. 9.

Fig. 11 is an end view of Fig. 9 with the end closure down.

Fig. 12 is a partial top sectional view showing the leaf spring latch for the end closure.

Fig. 13 is a sectional view taken along lines 13—13 to show the stop means for the end closure which provides a ramp to facilitate insertion of forms within the lower compartment of the invention.

Fig. 14 is a sectional view of a modification of a portion of the diaphragm.

Referring to the drawings, there is shown an order form holder 20 having a base member 21 with a closure member 22 connected to one side thereof by a hinge 23.

A diaphragm 24 has a hinge 25 formed by bending one end of the diaphragm about an elongated pin 26 with the other side of the hinge 27 being also formed about the elongated pin 26 and being secured to the bottom portion of the base member 21 by rivets such as 28. A U-shaped leaf spring 29 is secured by rivets 30 in the center thereof to the bottom portion of the base member 21, said leaf spring being bent so that the free ends thereof engage the underneath surface of the diaphragm 24 to urge said diaphragm upwardly so that the pad of order forms 31, shown dotted, may be gripped by the pad clip 32, which pad clip has a lower member 33 riveted to the free end of the diaphragm 24, while the upper member 34 of the pad clip 32 is hinged to the lower member 33 by a pin 35. Springs 36 urge the upper member against the lower member so that the pad of order forms 31 may be gripped therebetween.

A dash-dot line 37 represents at least one of the order forms of the pad of order forms which has been raised from the pad and placed on the upper surface of the closure 22, thereby permitting the dash-dot order form 37 to rest in a flat position on the closure member which acts as a writing platen when the device is in an operative position as shown in Fig. 3.

When the closure 22 is snapped into its operative position, as shown in Fig. 3, the spring 29 urges the diaphragm and its pad of order forms 31 upwardly against the underneath surface of the closure. A function of the upwardly urged diaphragm is to create friction on the pad of order forms by the closure member 22 so that the pad of order forms is pinched or gripped between the diaphragm and the closure member. When this condition exists, the form 31 may be withdrawn from the pad which is held by the pad clip 32 without dislodging the remainder of the order forms frictionally held between the diaphragm and the closure member. This condition simulates the holding of the unused forms of the pad by the hand to restrain the unused forms being withdrawn from the clip when the upper form is desired to be withdrawn from the pad clip 32 after the writing has been completed thereon. The used forms, as they are removed from the pad of order forms, may be stored underneath the diaphragm which provides a compartment therefor between said diaphragm and the bottom of the base member 21.

In the view shown in Fig. 3, one end of the diaphragm is hinged with the free end of said diaphragm being urged upwardly under action of the leaf spring 29.

A modification of the diaphragm support within the chamber of the holder is shown in Figs. 5, 6 and 7, wherein channel 38 is vertically disposed on each of two corners of the base member 21. The modified diaphragm 39 (Fig. 7) has one end thereof formed about an elongated pin 40, which pin extends from opposite sides of the diaphragm and is adapted to have said ends slideably engage the channel members 38 so that that particular end of the diaphragm may move up and down as the sales-slips or order forms are withdrawn from the pad and inserted beneath said diaphragm. An ear 41, which is part of the channel, is bent over the top of the channel to form a closure or limiting means so that the elongated pin 40 will not be removable from the channels 38 but may slide up and down therein as necessitated by placing the used order forms under the diaphragm and under influence of the leaf spring 29. The channels 38 are secured by rivets 42 to an end portion of the base member 21 as shown in Fig. 7.

The closure member 22 has one side of the hinge 23 formed thereon with the other side of the hinge 43 having a pair of elongated slots 44 formed therein, which slots are adapted to slide on headed pins 45, said pins 45 being secured to a side wall 46 of the base member 21. The length of the side of hinge 43 is such that it permits movement of the closure 22 so that said closure may be snapped into operative position as shown in Fig. 1, or snapped into its inoperative position as shown in solid lines in Fig. 4. The dotted lines (Fig. 4) of the closure member 22 show said closure member in its operative position.

The latch mechanism for the closure member has an elongated spring 47 which is shown in solid lines (Fig. 2). Elongated slots are formed adjacent opposite ends of the spring 47 so that pins 48, which are secured to the side wall 49 of the base member 21, will permit the spring 47 to be moved to its position shown dotted when the latch button 50 is depressed so that the spring 47 is moved to its unlatched position as shown in Figs. 2 and 6. The latch 51 carried by the spring 47 has an inclined surface on the upper portion thereof, as shown in Fig. 6, so that when

the closure 22 is moved to engage the latch 51 the spring 47 will be urged inwardly of the compartment of the holder until the latch 51 engages either its slot 52 when the closure member 22 is in its inoperative position, or may engage aperture 53 when the closure is moved to its operative position for writing on one of the pad forms positioned thereabove.

To open the holder, it is merely necessary to 10 depress the latch button 50 so that the spring 47 will be moved to the position shown in Fig. 6, thereby permitting the closure member 22 to be pivoted on its hinge 23 so that the closure member may be moved out of the way to permit access 15 to the order form pad.

A clip 54 is secured to the closure member by a rivet 55, and permits papers, cards or other material to be held thereby.

While the leaf spring 29 is shown in one form, 20 it is to be understood that any type of resilient member may be used for urging one end of the diaphragm against the underneath surface of the closure member 22, it being understood that any suitable means may be employed provided adequate friction is permitted for urging the unused 25 order forms against the underneath surface of the closure member 22.

From the foregoing it will be seen that the base 30 member 21 has a bottom portion with two side members and two end members, and a closure member slideably hinged adjacent one of the side members. The corners of the end and side members are shown secured by angular brackets 56 with rivets 57. However, it is to be understood 35 that any form of securing these members together may be used, such as by welding, or they may be held otherwise in relative position.

A modification of the device presented in Figs. 40 1 to 7 is shown in Figs. 8 to 13 and is a form of the invention particularly adapted for dispensing forms wherein as the top form is removed from the stack of forms the remaining forms or sales slips are urged into position to be removed successively as desired.

Like reference characters represent similar parts throughout the specification.

The writing platen 22 in the modified form of the invention has a retractile spring 60 having one end thereof connected to a lug 61 formed on 50 the side of hinge 43 with the other end of said spring 60 being connected to one of the headed pins 45, as shown in Figs. 9 and 10. When the latch button 50 is depressed to release the writing platen when in its inoperative position, the 55 spring 60 will immediately snap the writing platen into the position shown in Fig. 10. By properly positioning the headed pin 45, to which the spring 60 is attached, in its respective slot in the side of hinge 43, the writing platen is 60 provided with a limiting means so that the latch 51 will be in substantial registry with its latch slot 52. Thereafter a slight pressure on the upper surface of the writing platen will cause the latch 51 to engage in latch slot 52 and retain the writing platen in latched operative position as long 65 as the user so desires.

The modified diaphragm 62 shown in Figs. 8 to 11 has the free end 63 formed at an incline so that the forms gripped between the diaphragm 70 62 and the writing platen 22 as presented in Figs. 8 and 10, will be in staggered relation at one end thereof to facilitate removal of said forms from the device, the opposite end of said forms being held by the pad clip or clamp 64 positioned near 75 the diaphragm hinge end of hinge 26.

The lower member 65 of pad clip 64 is secured to the diaphragm 62 by inserting a nut and screw combination 66 through apertures in lower member 65 which are in registry with complementary apertures such as 67 formed in the diaphragm 62. The pad clip, or clamp, 64 is therefore movable to one of several positions to permit a variety of form sizes to be used without necessity of concern for desired operability of the invention.

In order to provide a modified arrangement with its attendant advantages, the U-shaped leaf spring 29 is shown in Figs. 9, 10 and 11 being secured to a bracket 68 by pins 30, said bracket being spaced from the bottom of the base member and being secured to the sides thereof. The U-shaped leaf spring engages an underneath surface of the free end 63 and urges the diaphragm 62 upwardly in the same manner as set forth for diaphragm 24.

The end closure 10 is movably mounted on the base member by a hinge 71 and may be swung to the open position in Fig. 10 (shown dotted) and Fig. 13 shown in solid lines to permit the used forms to be inserted between the bracket 68 and the base member for entry into the compartment between said base member and the diaphragm.

The end closure is latched in its closed position as shown in Fig. 12 by a leaf spring latch 72 secured to a side of the base member by pins 73. The free end of said latch 72 has a shoulder 74 which extends through an aperture 75 formed in the end closure 10 to hold the closure in its latched position as shown in solid lines of Fig. 12. The button 76 extends through the aperture of the side so that the leaf spring latch may be operated.

A pair of complementary stop means is positioned on either side of the hinge 71, and each pair consists of a stop 78 secured to the base member, and a stop 79 secured to the end closure 10 by pins 79. When the end closure 10 is down as shown in Fig. 13, it forms a ramp to guide and assist insertion of the forms into the lower compartment of the modification of the invention embracing the sales slip holder or forms dispenser.

Fig. 14 shows a modification of a portion of the diaphragm having an upturned lip 80 which may be used as one form of a restraining or limiting means for the stack of forms 81. When the lip 80 is employed, the clamp 64 may be eliminated since the pressure of the spring urged diaphragm against the writing platen underneath surface holds the stack of forms in place in the forms dispenser type of modification. Consequently when the upper form 82 is being withdrawn from the stack of forms 81, the remainder of said stack impinges the lip 80 and permits the uppermost form to be withdrawn without dislodging the remainder of the stack of forms. While the lip 80 may extend across the full width of the diaphragm, it is to be understood that any suitable type lip or lips, such as spaced fingers, may be utilized without departing from the spirit of the invention.

Further, it will be seen that the slideable closure member forms a writing deck and a hand rest which extends beyond the order form so that the hand of the writer may be adequately supported while writing at the very bottom of the order form or sales-slip. The rigid diaphragm, which may be formed of metal or fibre, may have one end thereof either hinged or disposed partially by channels as shown. However, it is to be understood that the invention is not limited thereto except as embraced by the spirit of the claims attached hereto.

Further, the member 22 has a dual purpose in that it is actually a writing platen and hand rest when clamped or latched in one position, and acts as a closure for the base member when latched in another position. When the member 22 is positioned to act as a writing platen it also acts as one side of a clamp to hold the unused forms between said writing platen and the diaphragm which acts as the opposite side of the clamp under influence of the leaf spring 29. Therefore, when the writing platen is clamped or latched in writing position the spring urged diaphragm clamps certain of the stack of forms between said platen and said diaphragm to facilitate removal of certain other of the forms from said stack.

What is claimed as new and desired to be secured by Letters Patent of the United States is:

1. A form holder of the class described comprising a base member, including a bottom, two end portions and two side portions, a closure member hingedly connected to one of said side portions and adapted to latch onto the other side portion of said base member, a latch means for securing said closure member to said base member, a substantially rigid diaphragm disposed within said holder and having means thereon to secure one end portion of said diaphragm to said base member, resilient means secured to said base member and adapted to urge the opposite end of said diaphragm toward said closure member, and means secured to said diaphragm to hold order forms thereon, said means for securing said one end portion of said diaphragm to said base member including pin means secured to said diaphragm, and channel guide means secured to the base member to receive said pin means, said closure member in one rotated position closing said holder against the biasing effect of said resilient means and in another rotated position exposing the interior of said holder.

2. A compartmentalized dispenser of the class described having a base member including an end closure hingedly connected thereto to form a ramp for facilitating insertion of forms within said dispenser, stop means for limiting the movement of said end closure in one direction, a writing platen positionable on said base member, a diaphragm disposed between said base member and said writing platen, means for gripping forms and positioning same on said diaphragm, resilient means for urging said diaphragm toward said writing platen, and latch means to hold said writing platen in either an operative or an inoperative position.

3. A sales slip holder of the class described comprising a base member including a bottom, two end portions and two side portions, a writing platen hingedly connected to one of said side portions and adapted to latch onto the other of said side portions, latch means for securing said writing platen in an operative position, and resilient means for automatically moving said writing platen into substantially an operative position for writing from an inoperative position.

4. A forms dispenser of the class described comprising a base member including a bottom, two end portions and two side portions, a writing platen movably connected to said base member, and a diaphragm movably connected internally of said device and having a portion extending beyond an edge of said writing platen to bend and provide staggered end relation of forms disposed on said diaphragm when the writing platen is in operative position.

5. A forms dispenser for sales slips and the like comprising a base member, a writing platen movably connected thereto and positionable in an operative or an inoperative position in relation to said base member, a diaphragm movably connected within said base member and having means for staggering one end of the forms carried by the dispenser when the writing platen is in its operative position, and means positionable on said diaphragm for holding the forms thereon to accommodate forms of varying sizes in suitable dispensing position when the dispenser writing platen is in operative position.

6. A forms dispenser for sales slips and the like comprising a base member, a writing platen movably connected thereto and positionable in an operative or an inoperative position in relation to said base member, a diaphragm movably connected within said base member, means for urging said diaphragm toward said writing platen, and an end closure hingedly connected to and forming part of said base member and to provide a guide for insertion of forms between said diaphragm and said base member when said end closure is open.

7. A sales slip holder and forms dispenser of the class described having a base member, a positionable writing platen movably connected to said base member and positionable to an operative position from an inoperative position, a diaphragm movably connected within said forms dispenser and having means thereon for gripping the form therewith, an end closure forming part of said base member and being hingedly connected thereto to provide a ramp for facilitating ingress of forms within said dispenser, and latch means for said end closure to maintain said end closure in fixed position when the writing platen is in its inoperative position.

8. A holder of the class described comprising a base member, a diaphragm for supporting writing sheets carried by said base member, and a closure member, said closure member having a writing platen area and being pivotal about an axis disposed at the side of said diaphragm and being thus rotatable to expose said diaphragm and said closure member being reciprocally related to said diaphragm in a direction parallel to said axis, whereby in one reciprocated position it serves to shield said diaphragm and in another reciprocated position it serves as a writing platen for paper sheets supported on said diaphragm, including a resilient element for biasing said diaphragm towards said closure member whereby writing sheets supported on said diaphragm are normally urged into close proximity to said closure member.

9. A holder as set forth in claim 8, including a latch means for securing said closure member in either of said reciprocated positions.

10. A holder as set forth in claim 8, including means for rendering said closure member reciprocative and rotative with respect to said diaphragm, comprising a hinge element, said closure member being pivoted to said hinge element, and means in said base element retaining said hinge element in slidable relation therewith.

11. A holder for forms comprising a housing member for accommodating a pad of forms and a cover for said housing member, hinge means for hingedly relating said cover to said housing member at an edge thereof, said cover being slidably related to said housing member substantially in the direction of the pivotal axis of said hinge means and within predetermined limits whereby said cover may be reciprocated with respect to said housing member within said limits to partially expose the interior thereof and being rotatable with respect to said housing member to fully expose the interior thereof.

12. A holder for forms as set forth in claim 11, including a pad support diaphragm in said housing member and means for biasing said diaphragm toward said cover.

13. A holder for forms comprising a housing member for accommodating a pad of forms and a cover for said housing member, hinge means for said cover whereby said cover is rotatable with respect to said housing member for full exposure of the interior thereof; said cover being slidably related to said housing member within predetermined limits for partially exposing the interior thereof; the direction of reciprocation of said cover being substantially in the direction of the pivotal axis of said hinge means.
